CAR COUPLER

William J. Metzger, East Cleveland, Ohio, assignor to National Malleable and Steel Castings Company, Cleveland, Ohio, a corporation of Ohio

Application August 16, 1954, Serial No. 449,991

9 Claims. (Cl. 213—148)

This invention pertains to car couplers and more particularly to improved anti-creep means for the lock of the coupler.

The invention is directed to a railway car coupler having a pivoted knuckle and a generally vertically movable lock for holding the knuckle in closed position. While the improvement is especially applicable to the A. A. R. (Association of American Railroads) bottom-operated, standard E coupler, it may also be incorporated in other couplers of similar construction.

In the bottom-operated A. A. R. standard E coupler, anti-creep means is provided for limiting undesired upward movement of the lock so as to avoid inadvertent unlocking of the knuckle. More specifically, the lock-lifter link of the coupler is provided at its upper end with a forwardly extending anti-creep abutment which is adapted for engagement with the underside of a rearwardly extending lug on the forward wall of the lock opening in the coupler head to limit undesired upward movement of the lock. Although this particular anti-creep structure is satisfactory under ordinary service conditions, it is not adequate when unusual service conditions are encountered, as for example, when the coupler is subjected to a combined end and vertical shock. Under combined end and vertical shock, the lock is thrown forwardly and upwardly, while the upper end of the lock-lifter link is cammed upwardly and rearwardly by the action of a trunnion on the link which is guided in a slot in the lock leg. This causes the anti-creep abutment on the lifter link to move from beneath the lug in the lock opening, thereby rendering the lock anti-creep ineffective and allowing the lock to move upwards out of locking position.

Therefore, it is a primary object of the invention to provide a car coupler anti-creep means that is positive in operation under all service conditions.

An additional object of the invention is to provide coupler anti-creep means that is particularly effective when the coupler is subjected to a combined end and vertical shock.

A further object is to provide improved coupler anti-creep means that is readily interchangeable with the anti-creep means used in present car couplers and which does not require any structural changes in the coupler head or the lock.

A still further object of the invention is to provide anti-creep means for a car coupler that is positive in action under all service conditions yet in no way interferes with intentional coupler operation.

A more specific object of the invention is to provide in a car coupler a locklifter link having an anti-creep abutment thereon which projects further forwardly than the anti-creep abutment on the present locklifter link used in the standard E coupler.

Another specific object of the invention is to provide a locklifter link for a car coupler having an anti-creep abutment thereon which is disposed lower in the coupler

2

head than the anti-creep abutment on the locklifter link now present in the standard E coupler.

The foregoing and other objects and advantages will become apparent from the following description taken in conjunction with the accompanying drawings, wherein:

Fig. 1 is a longitudinal vertical sectional view of a coupler embodying the invention, showing the parts in locked position.

Fig. 2 is a fragmentary detail view of the coupler illustrated in Fig. 1 showing the anti-creep engaged to preclude further upward movement of the lock. The lock has been shown in the position it assumes as the result of upward creeping movement or vertical shock being imparted to the coupler in service.

Fig. 3 is a vertical sectional view similar to Fig. 1, but illustrating the relative positions assumed by the lock and its actuating mechanism during preliminary operation of the coupler to intentionally unlock the same.

Fig. 4 is a fragmentary detail view similar to Fig. 2, but showing the type of locklifter link at present used in the A. A. R. standard E coupler, the lock being shown in the position it assumes as the result of upward creeping movement or vertical shock being imparted to the coupler in service.

Fig. 5 is a fragmentary vertical sectional view of the coupler shown in Fig. 1, showing the improved anti-creep in functioning position following the application of a combined end and vertical shock to the coupler.

Fig. 6 is a fragmentary sectional view similar to Fig. 4 showing the present locklifter link used in the A. A. R. standard E coupler and illustrating the disengagement of the anti-creep when the coupler is subjected to combined end and vertical shock.

Fig. 7 is a fragmentary vertical sectional view of the coupler shown in Fig. 1, the improved anti-creep having been moved out of active position by intentional actuation of the rotor lever.

Fig. 8 is a detail side elevational view of a locklifter link embodying the invention. For purposes of comparison, this view also shows in dot-dash the locklifter link in use at present in the A. A. R. standard E coupler.

Fig. 9 is a top plan view of a locklifter link embodying the invention.

Referring to the drawings, the coupler comprises a head 10 and a knuckle 12, which is pivotally connected to the head by means of the usual pivot pin 14. The knuckle comprises a tail portion 16 which, when the knuckle is in closed position, extends into a chamber 18 in the coupler head. Tail 16 is formed with a vertical lock engaging face 20 and a laterally extending projection or shelf 22. The knuckle is held in closed position by a substantially vertically movable lock 24, which in locked position rests on shelf 22 and on knuckle thrower 26. In this position the lock also engages face 20 on the knuckle tail and the adjacent side wall of the coupler head.

A chamber 28 is provided in the coupler head above the lock 24 for receiving the lock during lifting thereof out of locking relationship with the knuckle to permit opening of the latter. The lock has a depending portion or leg 30 which extends downwardly into opening 32 in the lower portion of the coupler head when the lock is in locking position. Leg 30 is swingable in a longitudinal direction when so disposed in opening 32.

Lock 24 is actuated by means of a locklifter mechanism which includes a locklifter link 34, rotor lever 36 and an uncoupling rod (not shown). Link member 34 (Fig. 8) comprises a shank portion 37 having a forwardly extending anti-creep shoulder 38 disposed at the upper end thereof. Shoulder 38 has a top abutment surface 38a which slopes downwardly in a forward direction and which is adapted for engagement with the underside of

anti-creep lug 40 on forward wall 42 of opening 32 to limit upward movement of lock 24 in the event that it should creep or accidentally bounce upwardly in service. Link 34 is pivotally and slidably connected at its upper end to the lock leg by means of trunnion 44 which is received in an upwardly and rearwardly sloping slot 46 in the lower portion of leg 30. It will be noted that the abutment surface 38a on shoulder 38 slopes downwardly relative to a horizontal plane containing the transverse center line or axis of trunnion 44, commencing substantially at said axis.

When lock leg 30 of lock 24 extends downwardly into opening 32 and locklifter link 34 is in reposed position, as shown in Fig. 1, the forward extremity of surface 38a extends forwardly beyond the forward extremity of the lock leg and may also extend forwardly beyond the forward extremity of the underside abutment surface on anti-creep lug 40. The lower end of link 34 comprises an eye portion 47 which is pivotally connected to bifurcated forwardly extending portion 48 of rotor lever 36 by means of rivet 50. The rearward end of rotor lever 36 has a hook portion 52 by means of which the lever is pivotally connected to cylindrical support 54 formed on the underside of the coupler head. It will be understood that the usual uncoupling rod (not shown) is connected to the rotor lever for actuation of the same.

Operation of the parts to effect intentional uncoupling of the coupler will now be described. Starting with the coupler parts in normal locked position, as seen in Fig. 1, actuation of the uncoupling rod (not shown) causes rotor lever 36 to pivot in a clockwise direction. The initial rotation of lever 36 moves the lower end of locklifter link 34 forwardly and upwardly, and simultaneously therewith causes trunnion 44 to move rearwardly and upwardly to the upper end of slot 46 in the lock leg, as seen in Fig. 3. It will be observed that during this movement link 34 not only pivots about trunnion 44, but is cammed upwardly and rearwardly relative to lug 40 through the action of slot 46. Thus, for a given amount of rotation of rotor lever 36, a substantial rearward withdrawal of shoulder 38 is effected but as seen in Fig. 3, shoulder 38 is not at this point clear of lug 40. Upon further rotation of rotor lever 36 from the position shown in Fig. 3, leg 30 is forced rearwardly and upwardly until it contacts rear wall 56 of opening 32, as shown in Fig. 7, in which position shoulder 38 is clear of lug 40. Continued rotation of lever 36 from its position in Fig. 7 forces lock 24 upwards to a position in which it is out of locking relation to the knuckle.

It has been found that the locklifter link now in use in the A. A. R. standard E coupler forms an effective anti-creep only under certain operating conditions. Fig. 4 illustrates the action of that link when the coupler is subjected to the condition in which the lock has been moved bodily upwardly by a vertical impact until the anti-creep shoulder on the lifter link engages the anti-creep lug on the coupler head to prevent further upward movement of the lock. It will be noted that lock leg 30 in Fig. 4 is in contact with rear wall 56 and, at the same time, trunnion 44 is disposed at the lower end of slot 46. With the parts in this position, positive engagement between anti-creep shoulder 38 on the lifter link and the anti-creep lug 40 on the coupler head is established, and further upward movement of lock 24 is precluded.

However, uncouplings have resulted when a coupler embodying the presently used locklifter link is subjected to a combined end and vertical shock, as for example when the cars bounce on a switch or cross-over and the train surges lengthwise simultaneously, or during a run-in of slack between cars having drooped couplers. The position of the coupler parts under these conditions is illustrated in Fig. 6. The end shock causes lock leg 30 to move forwardly into engagement with forward wall 42, if it was not already in that position and also causes

rotor lever 36 to rotate in a clockwise manner, which moves trunnion 44' of link 34' to the upper end of slot 46 in lock leg 30. The vertical shock results in the lock and the locklifter link 34' moving directly upwards as a unit. It will be apparent that abutment 38' has been withdrawn from beneath lug 40 on the coupler head and the lock is free to move upwardly to a position in which the knuckle is unlocked. It will be noted from Fig. 6 that the anti-creep is inoperative whenever trunnion 44' on the locklifter link is disposed in the upper end of slot 46 in the lock leg even though leg 30 is positioned forwardly in opening 32.

The invention corrects the above-mentioned defect in the action of the present locklifter link by providing a novel link having an anti-creep shoulder that is positive in action and will form an effective anti-creep under all conditions of service to which couplers are subjected. More specifically, the anti-creep shoulder on the locklifter link has been extended forwardly a greater amount than the anti-creep shoulder on the lifter link presently used in the A. A. R. standard E coupler. In addition, the top abutment surface of the shoulder has been positioned below the level of the abutment surface on the anti-creep shoulder of the presently used link and this surface has been sloped downwardly in a forward direction. Fig. 8 clearly shows the difference in structure between the present locklifter link, as used in the standard E coupler and the locklifter link embodying the invention, the standard link being shown in dot-dash.

Referring again to Fig. 6 which illustrates the locklifter link currently used in the A. A. R. standard E coupler, it will be noted that abutment 38' on the link and lug 40 on the coupler head narrowly miss engagement. It is apparent that engagement would be assured if abutment 38' were extended substantially forwardly from that shown. However, if such an extension of the anti-creep shoulder on the link 34' were made, there would arise the problem of avoiding functioning of the anti-creep during intentional uncoupling, particularly so during a fast uncoupling operation. In other words, rapid initial operation of the uncoupling mechanism so disposes the parts that locklifter link trunnion 44 is positioned at the top of lock leg slot 46, as shown in Fig. 3. At this instant lock leg 30 has not yet been moved from its forward position in lock leg opening 32. The moment trunnion 44 contacts the top of slot 46, it begins to exert a combined upward and rearward force against lock leg 30. However, since the upward force component substantially exceeds the rearward force component, leg 30 travels upwardly substantially faster than it does rearwardly and abutment 38' does not clear lug 40. Thus, merely extending the anti-creep shoulder forwardly on the present locklifter link would produce an inoperative device during rapid operation of the uncoupling mechanism because lock leg 30 would not be disposed sufficiently rearwardly to prevent engagement between the link anti-creep shoulder 38' and coupler head lug 40 by the time the shoulder reached the level of the underside of the lug. Anti-creep engagement could only be averted if leg 30 were disposed further rearwardly in opening 32 the instant the abutment surface on the link shoulder is level with the underside of lug 40.

Therefore, in accordance with the invention, the anti-creep shoulder on the lifter link has not only been extended a substantial amount forwardly, but the top abutment surface 38a of the shoulder has been materially lowered so as to allow more time for the shoulder to move out from under lug 40 during a fast uncoupling operation. During this extra time interval, trunnion 44 on the lifter link 34 forces lock leg 30 further rearwardly in opening 32 with the result that by the time shoulder 38 reaches the level of lug 40 it is disposed sufficiently rearwardly that engagement between the shoulder and lug is averted.

Accordingly, the invention assures that anti-creep

engagement will be effected even though the shock applied to the coupler moves trunnion 44 to the upper end of slot 46 and moves lock leg 30 forwardly in opening 32, as shown in Fig. 5. Such position of the parts may occur whenever the coupler is subjected to combined end and vertical shock. It will be noted from Fig. 5 that when trunnion 44 is disposed at the upper end of slot 46 abutment surface 38a on anti-creep shoulder 38 extends substantially as far forwardly as does the lower end of slot 46 in the lock leg.

The abutment surface 38a on the anti-creep shoulder of the lifter link 34 has been sloped downwardly in a forward direction from a horizontal plane passing through the axis of trunnion 44. Surface 38a commences approximately along a line forming a continuation of the axis of trunnion 44. This lowers the entire surface 38a relative to lug 40 and in particular substantially lowers the forward portion of this surface so that it has sufficient time to clear lug 40 during intentional actuation of the uncoupling mechanism to move the lock out of locking position.

To assist in tipping link 34 rearwardly during the time trunnion 44 is travelling up slot 46 and therefore diminish the possibility of trunnion 44 binding on the upper surface of slot 46, the link has been counterweighted along its rearward side as at 60 in Fig. 8.

The invention also provides a more positive anti-creep protection when the coupler is subjected to the more usual service conditions during which the lock may creep slowly upwardly or may be thrown upwardly by vertical shocks. This is apparent from a comparison of the anti-creep positions shown in Figs. 2 and 4. It will be noted that there is substantially more overlap between shoulder 38 and lug 40 in Fig. 2, which shows a coupler incorporating the invention, than there is between the corresponding parts in Fig. 4 wherein is shown the locklifter link that is currently used in the A. A. R. standard E coupler. Furthermore, in present car couplers, manufacturing tolerances produce considerable variation in the amount of overlap obtained between the locklifter anti-creep shoulder and the anti-creep lug on the coupler head. Considering only the tolerance permitted by gaging practice, it is possible to obtain as little as $\frac{3}{32}$ " overlap in existing couplers. With the invention wherein the anti-creep shoulder is extended substantially forwardly, the minimum overlap has been increased to $\frac{7}{32}$ ".

As will be seen from Figs. 1, 3, and 7, the invention in no way interferes with intentional unlocking of the knuckle as by actuation of the uncoupling rod. More particularly, in Fig. 7, which shows the critical condition on intentional uncoupling, wherein abutment 38 approaches the level of lug 40, it will be seen that a material separation exists between these parts, thereby ensuring positive disengagement of the anti-creep.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A car coupler comprising a head, a knuckle pivoted to said head, a lock in said head for maintaining said knuckle in closed position, said lock having a downwardly extending leg, said head having an opening for receiving said leg, said leg having clearance between the front and rear walls of said opening to allow forward and rearward displacement of said leg, a locklifter link operatively connected to said leg, and a rotor lever pivoted to said head and being pivotally connected to said link, said head having an abutment on the front wall of said opening, said link having a shoulder underlying said abutment when the lock is in locking position and link and lever are in reposed position, said link having a trunnion

extending into an upwardly and rearwardly sloping slot in said leg, said link being movable to a position in which said trunnion is disposed in the upper end of said slot, said shoulder when said lock leg is in engagement with the forward wall of said opening and said trunnion is in said last-mentioned position being partly withdrawn from beneath said abutment, said shoulder having a downwardly and forwardly sloping top surface for providing sufficient clearance between said abutment and said shoulder upon actuation of said lever to completely withdraw said shoulder from beneath said abutment during intentional unlocking of the coupler.

2. A car coupler in accordance with claim 1 in which said top surface of the shoulder on said link extends from a horizontal plane passing through the axis of said trunnion.

3. A car coupler in accordance with claim 1 in which the top surface of the shoulder on said link is disposed below a horizontal plane extending through the axis of said trunnion.

4. In a car coupler having a head, a knuckle mounted for pivotal movement in said head, a movable lock for maintaining said knuckle in closed position, said lock having a leg extending downwardly into an opening in said head, an anti-creep lug on the forward wall of said opening, said leg being swingable in a forward and rearward direction in said opening, a locklifter link operatively connected to said leg, said link having a trunnion extending through an elongated, upwardly and rearwardly extending slot in said leg, said trunnion occupying the lower end of said slot when the parts are in reposed position, said link having a forwardly extending anti-creep abutment, said abutment underlying said lug to limit undesired upward movement of said lock when said trunnion is caused to occupy the upper end of said slot and said leg is disposed against the forward wall in said opening, said abutment having a downwardly and forwardly sloping top surface to provide sufficient clearance between said lug and the forward end of said abutment to ensure complete withdrawal of said abutment from beneath said lug during intentional unlocking of the coupler.

5. A locklifter link for a car coupler, comprising a shank portion, a horizontal trunnion disposed near the upper end of said shank portion and extending laterally therefrom, and an anti-creep shoulder extending forwardly of said trunnion and having a top abutment surface which is disposed generally below a horizontal plane passing through the axis of said trunnion.

6. A locklifter link in accordance with claim 5 in which said abutment surface slopes downwardly in a forward direction commencing substantially at a line coinciding with the axis of said trunnion.

7. A car coupler in accordance with claim 1 in which said locklifter link is counterweighted on its rearward side to facilitate movement of said trunnion to the upper end of the slot in the lock upon actuation of said lever to unlock the coupler.

8. A car coupler in accordance with claim 1, wherein said top surface of said shoulder extends generally forwardly beyond the forward extremity of said lock leg when said link is in said reposed position in the coupler.

9. A car coupler in accordance with claim 4, wherein said top surface extends forwardly to substantially the forward extremity of said slot when said trunnion is caused to occupy said upper end of said slot.
